ATTORNEY

UNITED STATES PATENT OFFICE

WILLIAM NOBLE DICKINSON, OF LONG ISLAND, NEW YORK

RESPONSIVE SIGNAL SYSTEM

Application filed October 11, 1927. Serial No. 225,489.

My invention relates to responsive signals in which the operating or actuating member is illuminated by directed, reflected or permitted light thereby advising the operator that the signal is set and operable and has for its object the production of an operating member which will provide for a sure indication by reflected, directed or permitted light at the point of control or of observation as to whether the actuation of the mechanism has been accomplished, or is accomplishing the desired result or is indicating a condition.

In general the invention involves the use of an optical system, and a source of light by the aid of which transparent or translucent push buttons, handles, levers or the like may be illuminated under certain conditions of service.

The possible applications of the invention are numerous and I will describe a few and the manner of their operation. In doing so I would first call attention to the fact that in connection with the majority of signal or control push buttons, switch handles or mechanical movements, no indication is provided of the result of their actuation, and uncertainty ensues. I am aware of the fact that some snap or lever switches are marked for "On" or "Off" positions; that separate signal lights or small electric bulbs included within push buttons have been used in some cases; and that the addition of semaphores is customary with railroad switches, but I believe that my invention provides for a much more certain, reliable, convenient and economical indication and that in arrangements of the centralized control of a large number of electrical circuits or mechanical movements, greater speed in the manipulation of the actuating members may be attained with much less physical and mental fatigue.

Let us assume an executive's desk with one or more call buttons of the ordinary type located thereon. When a button is pressed, there is nothing to indicate that the call has been registered and if the response is not prompt, doubt ensues and inconvenience or confusion result. With my "responsive" con-

trol, the button would be immediately vitalized or illuminated on being pressed, clearly indicating that the circuit was in operative condition and that the call had been registered.

Elevator signals and control from floor landings or elsewhere have been worked out quite elaborately but ordinarily leave the person operating the signal or control entirely in doubt as to whether or not his operative action has proved effective. Even with the most elaborate and expensive systems of floor signals as installed in the largest office buildings, everyone has had the experience of pressing a floor button, forgetting whether he pressed the up or the down button. Pressing again, waiting some time without any idea as to whether his action has proved effective and with doubt in his mind as to whether the push button contacts are operative, and of seeing one or more other persons approach the same landing and again push one or both buttons, having no knowledge of what action has previously been taken. With the "responsive" system installed, this entire situation would be remedied with resultant satisfaction to the users of the elevators and saving of contact wear in the signal system. It could also be accomplished in many cases without extensive changes in the push button boxes or in the signal system.

In connection with elevators controlled by push buttons my "responsive" system is also applicable to advantage in connection with what are known as house elevators and which are now used in apartment houses, a separate feature could be added which in the event of failure of immediate response would indicate clearly the cause of the failure to respond; that is, whether defective circuit lack of current, door or gate open, or elevator in use.

A large number of circuits could be handled within a small panel space, with clear indication of the setting of each signal or control and without requiring the eye to encompass more than one spot for each operation and its resultant signal.

The foregoing and other features of my invention will now be described in connec-

tion with the accompanying drawings forming part of this specification in which I have diagrammatically illustrated various modifications of my responsive signals which I may employ in the carrying out of my invention, after which I shall point out in the claims those features which I believe to be new and of my own invention.

In the drawings:

10 Figure 1 is a diagrammatical sketch illustrating the relation of the source of light, the optical system and the operating member which I employ.

15 Figure 2 is a diagrammatical sketch showing a simple electrical system in which the light is reflected on the button.

Figure 3 is a diagrammatical sketch showing a simple system in which the light is permitted to directly illuminate the button.

20 Figure 4 is a front view of a typical two push button plate used in elevator systems, one button as "Up" button and one button as "Down" button.

Figure 5 is a diagrammatical sketch showing a mechanical operation in which the light is directed by a prism on the surface to be illuminated.

Figure 6 is a modification employed in a 25 multiple control in which the operating member moves in steps.

Figure 7 is a plan view, and Figure 8 is a sectional elevation showing a modified form of multiple control in which the operating member is designed to rotate.

30 In the carrying out of my invention I employ an operating member 10 provided with a transparent or translucent face 11, a source of light 20 and an optical system comprising means 30 to reflect, direct or permit the light rays to illuminate the face 11 of the operating member 10.

35 In Figures 2 and 3 I illustrate my invention as applied to a simple annunciator, bell or buzzer circuit, in which the source of light 20 is connected in series with the annunciator 40, the latter being operated by battery 41 when the button 10 is pressed. When the button closes the annunciator circuit the source of light is reflected by the mirror 30, (Figure 2) to the button 10 and illuminates the surface 11. Even though the finger covers the entire face of the button when pressure is applied the illuminating is observable through the point of the finger,

40 indicating that the button has been vitalized. With this arrangement the button is vitalized only during the time that the pressure on the button persists. By using any of the well known circuits this may be changed so that the button becomes vitalized as soon as pressed, and so remains until the annunciator at the receiving station is returned to its original position by some one at that station.

45 In Figure 5 I have shown a mechanical

switch which when in one position the light 20 is directed by the prism 31 on the surface to be illuminated 11 of the switch or lever 10.

50 In Figure 6 I show my push button 10 provided with a reflector 32 and light baffles 42 having openings 43 and a plurality of light sources indicating a plurality of operating circuits. As the button is pressed inward, it will successively reflect light from the different sources, located at the different levels, each source being segregated from the other by means of the light baffles 42.

55 In Figures 7 and 8 I show my invention as employed to supervise a large number of electrical circuits indicated by the lights 20 through a single observation point. In this case the lights 20 are arranged in a circle. The circle may be large, as will be readily understood to accommodate as many signal lights as may be convenient or desirable. In 60 the central sleeve 50 the push button 10 is adapted to turn. The baffles segregate the lights as previously explained. By simply turning the button the lights will successively illuminate the single source of control 65 or operation. If the condition which it was desired to supervise was indicated by the lighting of the signal lamps it will be apparent that the lighting of any one signal lamp on the circumference of the circle would vitalize or illuminate the single observation point at the face of the operating member. By arranging the lamps at different levels and decks it will be apparent that the number of 70 circuits which may be supervised at a single 75 observation point may be indefinitely increased.

80 I have used the term "actuating member" to mean any push button, lever or other control member capable of assuming more 85 than one position. This may or may not operate an electrical circuit to light the lamp which may be reflected through the actuating member to the face to be illuminated. My 90 actuating member may be capable of longitudinal, horizontal or rotary movement.

95 It will be readily understood that the actual work of the equipment may be performed by magnets, motors, manually operated devices, steam or compressed air. My system is 100 simply to provide a means at the source to notify the operator that what he desires to be accomplished is being attended to and to know that such condition exists.

105 I do not wish to limit myself to the form 110 of baffles illustrated in Figures 6 and 8, for I may employ any trap or shutter arrangement which is operated by the operating means to allow the light rays to be projected 115 on the surface to be illuminated.

I claim:

120 1. In a signal or supervising system, the combination of an actuating member with a translucent portion capable of being illuminated from within and an optical system for 125 130

directing the rays of light to said translucent portion through the actuating member.

2. In a signal or supervising system the combination of an actuating member having a plurality of operating positions provided with a dial portion capable of being illuminated from within, a plurality of light sources, an optical system for directing the light from any source to said illuminable portion upon movement of the actuating member.

10 3. In a signal or supervising system, an actuating member with a face capable of being illuminated from within, said actuating member capable of assuming a plurality of positions, an optical system capable of directing rays of light to the face of the actuating member through the member, upon the operation of the actuating member.

20 4. In a signal or supervising system the combination of an actuating member with a translucent portion capable of being illuminated from within, said actuating member capable of being rotated to assume a plurality of positions, an optical system for directing the rays of light to said translucent surface through the actuating member from any reflecting angle.

In testimony whereof I affix my signature.
WILLIAM NOBLE DICKINSON.
